UNITED STATES PATENT OFFICE.

CHARLES B. MOORE, OF NEWTON CENTER, AND GEORGE B. TOTMAN, OF WOLLASTON, MASSACHUSETTS.

FEED-REGULATOR.

SPECIFICATION forming part of Letters Patent No. 700,219, dated May 20, 1902.

Application filed August 29, 1901. Serial No. 73,701. (No model.)

To all whom it may concern:

Be it known that we, CHARLES B. MOORE, of Newton Center, in the county of Middlesex, and GEORGE B. TOTMAN, of Wollaston, in the 5 county of Norfolk, State of Massachusetts, have invented a certain new and useful Improvement in Feed-Regulators, of which the following is a specification, reference being had therein to the accompanying drawing.

10 This invention relates to improvements in feed-regulators whereby the feeding of fluids may be regulated. The invention as herein described relates particularly to feed-regulators for steam-boilers, whereby the supply 15 of water for the boiler may be automatically controlled.

One object of the invention is to provide a simple and sensitive automatic feed-regulator.

20 Another object of the invention is to so construct a feed-regulator for steam-boilers that the controlling mechanism thereof may be directly effected from the water-column.

Another object of the invention is to so construct a feed-regulator that upon the falling 25 of the water in the water-column below a predetermined point the inlet-valve will be automatically opened.

The invention consists in the water-column, 30 the tube extending into the water-column, the float-chamber mounted on said tube and having the elongated stuffing-box, and a bucket-float within said float-chamber and having a rod rigidly secured to said bucket 35 extending through the perforation in the bushing.

The invention still further consists in such other novel features of construction and combination of parts as shall hereinafter be more 40 fully described, and pointed out in the claim.

The drawing represents a view of a portion 45 of a steam-boiler with a sectional view of the water-column thereof and the improved regulator mounted on the column and connected with a balanced valve in the water-feed pipe.

In the drawing, 5 represents a portion of any ordinary boiler or other device or mechanism adapted to receive a fluid-supply, 6 indicating the fluid-supply pipe, which is controlled by any ordinary balanced valve. In

the present instance the valve-stem 7 is shown as furnished with the lever 8, carrying the balance-weight 9.

Mounted on the boiler or other receptacle 5 is the water-column 10, of any usual construction and connected in the ordinary manner with the boiler or receptacle 5. This column 10 has the usual gage-cocks 11, 12, and 13 and the gage-tube 14, connecting with the interior of the column for determining the height of water in the boiler. Preferably in the top of the column is formed an opening in which the bushing 15 is screwed, and in this bushing is screwed the tube 16 in the nature of gage-pipe, the lower open end of which extends down into the column 10 to a point approximately opposite the gage-cock 12. On the upper end of the tube 16 is mounted the chamber 17, furnished with the top 18, secured to such chamber with a steam-tight joint and having the laterally-extending arm 19. In the center of this top 18 and axially disposed with relation to the tube 16 is an opening in which is secured the bushing 20 in the nature of an elongated guide-tube, 70 having the enlarged shoulder 21 and provided at its outer end with the compression-cap 22 to form a stuffing-box. Through the long perforation in bushing 20 is freely movable the rod or stem 23, having at its upper end slotted ears, as 24, and fixed at its lower end in the conical weighted bottom 25 of the bucket 26. 75

On the upwardly-extending portion 19' of the arm 19 is pivoted the lever 27, carrying the adjustable balance-weight 28, this lever 85 being furnished with pivots which are engaged in the slots of the ears, as 24, of the rod or stem 23 at one end, and at the other end being connected by the rod 29 with the lever 8 of the herein-shown balanced valve, 90 or said lever 27 may be operatively connected in any desired manner with any other valve adapted to be actuated or controlled by the movement of said lever.

It is obvious that the height of the chamber 17 must be such that the desired movement of the bucket 26 may be effected. It is also understood that any ordinary valve may be introduced between the column 10 and the chamber 17 when such becomes nec- 100

essary or desirable and that said chamber 17 may be furnished with a petcock 30.

The operation of the device is as follows: Water is introduced into the boiler and enters the water-column 10 by the usual connections, filling the column 10 and passing through the tube 16 to fill the chamber 17 and its bucket-float 26. The connections between the rod 23 and the supply-valve are now adjusted in proper relation. When the water-level in the boiler falls to a point where the water-level in the column 10 drops below the end of the tube 16, the water in such tube also falls and a vacuum is created at the upper part of the chamber 17, the bucket 26 will begin to rise, and the rod or stem 23 will lift this end of the lever, and through the connections the supply-valve will be partially opened, water will enter the boiler, and the column of water in the gage pipe or tube 16 will move upward, causing the filling of the chamber 17 and allowing the bucket 26 to drop sufficiently to cause the closing of the

supply-valve through the connections therewith.

Having thus described our invention, we claim as new and desire to secure by Letters Patent—

The combination with the column 10, the gage pipe, or tube, 16 extending therein and furnished with the float-chamber 17, the cover 18 for said chamber, and the elongated stuffing-box and guide 20 secured in a perforation of such cover, of the bucket 26 having the weighted bottom 25, the stem 23 rigidly secured in said bottom and working through the stuffing-box 20, and controlling connections for connecting said stem 23 with a supply-valve.

In testimony whereof we affix our signatures in presence of two witnesses.

CHARLES B. MOORE.
GEORGE B. TOTMAN.
